UNITED STATES PATENT OFFICE.

ALFRED H. KUDLICH, OF LYNN, MASSACHUSETTS, ASSIGNOR TO GENERAL ELECTRIC COMPANY, A CORPORATION OF NEW YORK.

TURBINE-BUCKET.

974,160.

Specification of Letters Patent. Patented Nov. 1, 1910.

Application filed August 15, 1907. Serial No. 388,639.

To all whom it may concern:

Be it known that I, ALFRED H. KUDLICH, a citizen of the United States, residing at Lynn, county of Essex, State of Massachusetts, have invented certain new and useful Improvements in Turbine-Buckets, of which the following is a specification.

This invention relates to elastic fluid turbines, in which the rotating element is provided with a plurality of curved blades upon which the steam impinges. It is customary, in large units, to make the blades separate and secure them in rows upon the periphery of the bucket wheel. A common mode of fastening the bucket is to cut away one end of it to form a dovetailed tenon which is inserted in an undercut groove in the edge of the bucket wheel, or in a segment which is afterward attached to the wheel. The cutting of the tenon wastes a considerable quantity of the metal, and one of the objects of my invention is to prevent this waste. Furthermore, owing to the thinning of the bucket toward its edges, the tips of the dovetailed tenon are its narrowest and weakest portions, whereas the parts which engage the lowest part of the side walls of the undercut groove should be the strongest, because at that point there is a greater thickness of metal in the wheel to resist centrifugal force. When it is remembered that a bucket weighing one pound mounted on the periphery of a twelve foot wheel making 600 revolutions per minute exerts a centrifugal force of 736 pounds, the necessity for a strong and unyielding fastening becomes apparent. A further object, therefore, of my invention, is to strengthen the parts which retain the bucket in the groove.

I accomplish the results aimed at by slotting the sides of the bucket in toward the middle thereof, leaving sufficient metal between the inner ends of the slots to fill the narrow mouth of the undercut groove in the bucket-wheel or segment. The horns produced by these slots are then bent in a forward and backward direction beyond the plane of the bucket, and preferably toward the concave side of the bucket so that their outer edges are parallel and stand just far enough apart to fit against the side walls of the undercut portion of the groove. The customary spacing blocks are interposed between the bases of the adjacent buckets.

In the accompanying drawings, Figure 1 is a side elevation, partly in section, of a portion of a bucket wheel and a few buckets secured thereto after the manner of my invention; Fig. 2 is a longitudinal cross-section 60 thereof, on the line 2-2, Fig. 1; Fig. 3 is a radial cross-section on the line 3-3, Fig. 2; and Fig. 4 is a perspective view of one of the buckets.

The wheel 1 has an undercut groove in its 65 periphery. At some convenient point the side of the wheel is cut away to form a lateral inlet to said groove. This inlet is closed by a block 2, conforming to the shape of the groove and secured by a transverse rivet 3. 70 The bucket 4 has two oppositely located slots 5 extending into its sides parallel with and near its bottom. The portion of the neck or shank 6 of the bucket between the inner ends of said slots is just wide enough to 75 fit snugly in the narrow mouth of the undercut groove in the wheel. The horns 7 formed on the lower end of the neck or shank by cutting these slots are then bent beyond the plane of the bucket and preferably both toward the concave side of the bucket until their outer sides stand parallel with each other; that is, transverse to a line joining the outer edges of the bucket. The outer walls of the groove are of the proper 80 height to receive these horns, so that they lie snugly between the bottom of the groove and the overhanging metal above. The upper edges of the horns afford a long bearing surface to resist the radial strain on the bucket 85 due to centrifugal force.

The buckets are assembled in the groove by removing the block 2 and slipping the buckets in laterally through the inlet and then sliding them along the groove. Spacing or filling blocks 8 are interposed between adjacent buckets, fitting also between the horns 7. If desired, the pitch may be regulated by machining off the tips of the horns 90 so that the length of the horns is the same on all the buckets. The tips of the horns on one bucket are then abutted against the convex back of the next bucket, thus spacing all the buckets at equal distances. The filling between the buckets may then be effected 100 by pouring in melted type-metal or the like, instead of using solid blocks slipped in alternately with the buckets.

It will be seen that the above-described construction cuts down stresses in the blade 110

or bucket to something like 25% and affords greater utilization of stock by increase of holding surface thereby affording a much stronger fastening for the buckets.

5 In accordance with the provisions of the patent statutes, I have described the principle of operation of my device together with the apparatus which I now consider to represent the best embodiment thereof; but I desire to have it understood that the apparatus shown is only illustrative, and that the invention can be carried out by other means.

What I claim as new and desire to secure by Letters Patent of the United States, is,—

15 1. A turbine bucket, the middle portion of which is thicker than its edges, said bucket having its base provided with a neck of less width than the bucket and of the same thickness as the adjoining portion of 20 the body of the bucket, and horns extending from the base in a direction transverse to a line joining the outer edges of the bucket.

2. A curved turbine bucket the middle 25 portion of which is thicker than its edges, said bucket having its base formed from a neck projecting from its middle portion and horns on the outer end of the neck extending in a forward and backward direction beyond 30 the body of the bucket.

3. A curved turbine bucket the middle portion of which is thicker than its edges, said bucket having its base provided with a neck projecting from said middle portion 35 that is of less width than the bucket and horns extending from the outer end of the neck on the concave side of the bucket with their outer faces parallel.

4. The combination with a turbine wheel 40 having an undercut groove, of a turbine bucket having forwardly extending horns whose outer sides are parallel and whose upper edges fit under the over-hanging portion of said groove.

45 5. The combination with a turbine wheel having an undercut groove, of a bucket provided with holding members which extend along said groove beyond the plane of said bucket and engage the walls of the groove.

50 6. The combination with a turbine wheel having an undercut groove, of a bucket having horns at its lower end which extend along said groove.

7. The combination with a turbine wheel 55 having an undercut groove, of a plurality

of buckets, each having horns which extend along said groove, and abut against the next bucket.

8. The combination with a turbine wheel having an undercut groove, of a plurality 60 of buckets each having horns which extend along said groove, and filling between said buckets and between said horns.

9. The combination with a turbine wheel having an undercut groove, of a plurality of 65 buckets each having horns lying in said groove and abutting against the next bucket, and fusible material filling the spaces between said buckets.

10. A turbine bucket having a substantially 70 central neck or shank of less width than the portions of the bucket above and below said neck or shank, one of said portions being provided with parallel retaining horns extending in a direction transverse to 75 the face of the bucket.

11. A curved turbine bucket having a body the middle portion of which is thicker than its edges, a substantially centrally arranged neck projecting downward from the 80 body which is of less width than the body and has the same thickness and curvature as the corresponding part of said body, and horns extending from each side of the lower end of the neck in a direction transverse to 85 the faces of the bucket.

12. A curved turbine bucket having a body the middle portion of which is thicker than its edges, a neck forming an extension from the middle portion of the body that 90 is of less width than said body, and horns projecting from each side of the neck in a direction transverse to the faces of the bucket, the distance between the outer faces of the horns being greater than the width 95 of the neck.

13. The combination with a turbine wheel having an undercut groove in its periphery, of buckets having their bases secured in the 100 groove, each base comprising a neck which engages the narrow portion of the groove and horns that project from the neck and extend along the groove in engagement with the overhanging walls of said groove.

In witness whereof, I have hereunto set 105 my hand this twelfth day of August, 1907.

ALFRED H. KUDLICH.
